TOY MOUSE FIGURE

Anna Edwarda Mosczynski, New York, N. Y.

Application August 16, 1957, Serial No. 47,410

Term of patent 14 years

(Cl. D34—2)

Fig. 1 is a front view of a toy mouse figure embodying my design; and

Fig. 2 is a side view thereof.

The characteristic features of the design reside in those features shown in solid line.

I claim:

The ornamental design for a toy mouse figure, as shown and described.
